UNITED STATES PATENT OFFICE.

WILLIAM TURNER, OF WENATCHEE, WASHINGTON.

CURRENT-MOTOR.

SPECIFICATION forming part of Letters Patent No. 625,220, dated May 16, 1899.

Application filed May 7, 1898. Serial No. 680,060. (No model.)

To all whom it may concern:

Be it known that I, WILLIAM TURNER, a citizen of the United States, residing at Wenatchee, in the county of Kittitas and State of Washington, have invented certain new and useful Improvements in Current-Motors; and I do hereby declare the following to be a full, clear, and exact description of the invention, such as will enable others skilled in the art to which it appertains to make and use the same.

This invention relates to current-motors; and it consists of the construction and arrangement of parts more fully hereinafter described and claimed.

The object of the invention is to so arrange a current-motor that power may be transmitted from opposite sides thereof for driving machinery generally, and thereby utilize the current of a river or other body of water in the several arts and manufactures at a minimum cost as well as for general irrigating purposes.

In the accompanying drawings, Figure 1 is a top plan view of a current-motor embodying the invention. Fig. 2 is a bottom plan view of the same. Fig. 3 is a longitudinal vertical section. Fig. 4 is a rear end elevation. Fig. 5 is a transverse vertical section. Fig. 6 is a detail perspective view of one of the propelling-paddles. Fig. 7 is a similar view of a slight modification in the construction of the paddles. Fig. 8 is a detail perspective view of one of the end hangers. Fig. 9 is a similar view of one of the hangers applied to the end of the motor opposite to that at which the hanger shown by Fig. 8 is used.

Referring to the drawings, wherein similar numerals of reference are employed to indicate corresponding parts in the several views, the numerals 1 and 2 designate outer side floats, which, as shown, are rectangular in form and hollow, as clearly illustrated in Fig. 5. Extending upwardly from the front ends of the floats 1 and 2 are supporting float-arms 3, which are converged toward each other and serve as protectors for the adjacent mechanism and also to receive a front fender 4, which closes in the front end of the motor and extends backwardly on opposite sides over the opposite portions of the floats 1 and 2. This fender serves to prevent the mechanism from becoming entangled with or injured by logs

or debris and is so inclined at all points at the front as to deflect such material either to one side or the other and clear the motor. 55 The fender is extended rearward a sufficient distance to prevent lodgment of debris against the outside of the floats 1 and 2, and at all points said fender extends downwardly and deep enough to also prevent floating material 60 from passing under the motor. By this means the paddles, which will be hereinafter referred to, are unimpeded in their action and continuously receive the full force of the current and maintain thereby a steady opera- 65 tion of the driving mechanism. As more clearly shown in Fig. 5, the outer floats 1 and 2 are connected to inner hollow floats 5 by suitable upper and lower tie-plates 6, the said inner floats 5 being spaced apart from each other at the center to form a waterway 7, for a purpose which will be hereinafter set forth. On the top of the floats 5 a metal or other suitable sheathing 8 is secured and covers the central open space between the said floats and 75 also acts as a wear-plate for the paddles or propellers.

Extending outwardly from the end floats of the central series are bearing-arms 9, in which the opposite ends of shafts 10 and 11 are journaled, the said shafts being intermediately braced by braces 12, having their free ends engaging grooves 13 in the said shafts. On the opposite sides of each of the shafts sprocket-wheels 14 are keyed and are engaged by endless chains 15, to which are secured the paddles or propellers 16, arranged at regular intervals. These paddles or propellers are shown in detail in Figs. 6 and 7, and in each instance they are substantially rectangular and hollow, 90 having two sides removed and so arranged on the endless chains 15 as to bring the said open portions thereof directly against the current. To position the said blades or propellers in this manner, fastening devices for attachment 95 to the endless chains 15 are arranged on diagonal lines relative to the contour of said paddles, and, as shown in Fig. 6, the said fastening devices are in the form of enlarged substantially U-shaped staples 17, having the 100 legs 18 projected outwardly beyond the ends and headed, as at 19. The legs 18 of the staples 17 are held in the links of the endless chains 15 and the heads 19 afterward formed to es-

tablish a connection. As a convenient mode of forming the said paddles or propellers each comprises flat strips of metal 20, having angularly-bent ends 21, and when joined the 5 said strips are placed at right angles to each other, and the opposite ends of one strip lie against the inner surfaces of the similar ends of the other strip, and to accommodate this arrangement one strip is made slightly shorter 10 than the other. The staples 17 hold the parts together, and the overlapped angularly-bent ends of the two strips stiffen and reinforce each paddle or propeller against bending. In 15 Fig. 7 the form of the paddle or propeller is slightly modified in that rods 22, which extend entirely through each paddle from end to end, are substituted for the staples 17, and in this instance, as in the construction shown by Fig. 6, the ends 23 of the rods project exteriorly and are headed. As previously set forth, the open sides of the several paddles or propellers receive the impact of the current, and a number of the same will be located under the motor at one and the same time, and 20 when lifting around the shafts 10 and 11 they are placed in such position as to entirely free themselves of water to avoid lifting by the mechanism of any extra weight, and thereby overcome as much resistance as possible. In 25 moving over the upper portion of the motor the paddles or propellers travel or bear upon the metallic sheathing 8, and the open space 7 permits the water to flow through the motor and removes all liability of a dam resistance. 30 As set forth, the outer ends of the shafts 10 and 11 are held by bearing-arms 9, and outside of said arms said shafts have sprocket-wheels 25 fixed thereto, which are engaged by chain belts 26, running to smaller sprocket-wheels 27 on drive-shafts 28, mounted in 35 bearings 29 on the outside floats 1 and 2. A part of these shafts 28 have two pulleys or band-wheels 30 thereon, while the remaining portion only have one of said pulleys or band-wheels 30. These pulleys or band-wheels could be replaced by sprocket-wheels or other transmitting-gearing, and in the present instance the form of such devices employed is adapted to be engaged by belts, (not shown,) 40 which run to a distance from the motor and transmit the power generated by the paddles or propellers 16 through the shafts 10 and 11 for any desirable use, such as running machinery or the mechanism of an electric-light plant. On the shafts 28, on one 45 end of the motor, inner friction-wheels 31 are keyed, and at a suitable distance therefrom are shorter shafts 32, also having friction-wheels 33 on the same in alinement with the 50 wheels 31. On the shafts 32 drums 34 are also fastened and have the upper ends of adjusting-chains 35 secured thereto, which run downwardly through depending hanger-yokes 36, having grooved pulleys 37 to ease the 55 movement of the said chains. Adjacent to the friction-rollers 31 and 33 a lever 38 is pivotally mounted and carries a stub-shaft 39,

on which a connecting-roller 40 has rotation. The free end of the lever is adjustably mounted in a corrugated open standard 41 and, as 70 shown in Fig. 5, is cut away at its upper portion, as at 42, to permit the bends of the standard to engage and hold the said lever in its adjusted position. Adjacent to each of the rollers 33 and forming a part thereof are 75 ratchet-faces 42^a, which are engaged by pawls 43. The lower ends of the adjusting-chains 35 are attached to opposite portions of a stay-chain 43^a, which is connected at opposite ends to stakes or posts 44, driven into the opposite 80 banks of the river or other stream in which the motor is located, and when properly positioned or anchored the said stay-chain is drawn taut and located some distance below the under portion of the motor. At the opposite end of the motor similar adjusting-chains 35 are attached to drums 34; but the rollers 33 are reversed in position to those previously described, though carried by similar shafts 32. The said rollers 33, however, differ from those 90 heretofore set forth in that they are provided with a series of circumferential openings 45, adapted to be removably engaged by hand-bars 46. A ratchet 42^a also forms part of the roller 33 in this instance, and a pawl 43 engages the said ratchet 42^a. On the shafts 28 at 95 this end of the motor rollers 45 are secured, similar to the rollers 31, which may be used for any purpose and either assist in transmitting the power from the drive-shaft on which they 100 are located or for attachments imparting motion to other attachments that may be mounted on the motor. The adjusting-chains 35 at this end of the motor extend downwardly through hangers 47 and are attached to a second stay-chain 48, which is arranged similar 105 to that heretofore described and extends under the motor similarly to the stay-chain 43^a, being in like manner fastened at its opposite ends by means of posts 44, also driven into 110 the adjacent bank. One of the hangers 36 is shown in detail, Fig. 9, and consists of an elongated U-shaped metallic frame, with upper angular bent ends 48 and 49. The end 48 extends at a direct right angle, and the 115 end 49 is in a plane at right angles to the end 48, being so positioned by a lateral extension 50, and is adapted to pass over and be secured 120 against the front ends of the outside floats 1 and 2, as clearly shown in Fig. 1. The ends 120 48 are secured to adjacent portions of the floats 5, and the lower portion of each of the said hangers is flattened, as at 51, and apertured to receive the bearings for the pulleys 37. One of the hangers 47 is shown by Fig. 8 125 and differs slightly in construction from the hangers 36 in that the upper part of each side thereof is bent inwardly, as at 52, and then extends upwardly and outwardly, as at 53, the outwardly-extending portions being in horizontal planes and one longer than the other for securement to the adjacent parts of the 130 floats 1, 2, and 5.

On one or both of the outside floats 1 and

2 is a winding device consisting of a counter-shaft 54 in bearings 55, and on the rear end is a beveled gear 56, which is adapted to mesh with a similar gear 57 on the outer portion of the shaft 28. A winding-drum 58 is loosely mounted on said shaft 54 and has a clutch member 59 thereon, which is adapted to be engaged by a second clutch member 60, adjustable on the said shaft 54 and operated by a clutch-lever 61, pivotally mounted on the float. The accompanying drawings show a winding device of the character specified on each side to show that the said mechanism is adapted for use on both sides of the motor; but under ordinary circumstances only one of the same will be necessary. The function of this winding device is to assist in drawing a foot-bridge or other devices toward the motor from the adjacent bank, or it may be equally well employed for other purposes, and in operation the gear 56 rotates the shaft 54 through the medium of the gear 57, and when the clutch members 59 and 60 are in engagement the drum 58 is rotated, and by disengaging the said clutch the said drum may run loose for unwinding purposes.

On one side of the motor adjacent the rear end a water-elevator 62 is mounted and consists of an inclined frame 63, having opposite sides, with lower slotted or bifurcated ends 64, as clearly shown in Fig. 3, which fit over the shaft 11 on the outer side of the endless chain 15. Within the said frame 63 is an endless chain 65, which carries a series of buckets 66, arranged at regular intervals and movable over an upper chain-wheel 67. The frame 63 is supported by an upright 68, which is removably fitted in a clip 69 on an adjacent portion of one of the floats, and at the upper end said upright is permanently secured to said frame. Hanger-rods 70 extend downwardly from the upper end of the frame 63 and suitably support a trough or chute 71, which is adapted to extend over from one side of the motor, as shown in Fig. 1, to any distance away therefrom and preferably to one bank of the stream in which the motor is located, where the water from the trough runs into a sluiceway or other conduit overland to any suitable distance for the purpose of irrigation or other use. The elevator 62 is removable from the motor, and while it is shown applied to one side of the same it may be equally well positioned at any other point or duplicated on opposite sides without requiring any material change in the construction and arrangement of parts. The endless chain 65 of the elevator is operated by a suitable sprocket on the shaft 11, and the water is elevated by the buckets 66 and delivered in the trough or chute 71.

As previously noted, power may be transmitted from the drive-shafts 28, and when frictional mechanism is employed, as shown at one end of the motor, the drums 34 can be operated to wind the adjusting-chains 35 thereon and properly hold the motor down

in the stream in a predetermined position and in such manner as to be best influenced by the current. In releasing the adjusting-chains the friction-wheels 40 are disengaged through the movement of the levers 38 and the pawls 43 are released from the ratchets 42. The same operation of the drums 34 at the opposite end of the machine can be accomplished by operating the hand-bars 46 and rotating rollers 45.

The power of the machine can be distributed to any point from opposite sides, and all the drive-shafts 28 are adapted to be simultaneously used or employed for operating other machinery, or one or more of the same without the others could be so utilized. The paddles or propellers 16 are large and impart considerable rotative power to the shafts 10 and 11, which is regularly transferred therefrom to the several drive-shafts.

Changes in the proportions, dimensions, and minor details of construction might be resorted to without in the least departing from the nature or spirit of the invention or sacrificing any of the advantages thereof.

Having thus described the invention, what is claimed as new is—

1. In a current-motor of the character set forth, the combination of outer and inner floats, adjusting-chains depending therefrom, and under stay-chains anchored at opposite ends and to which the said adjusting-chains are connected.

2. In a current-motor of the character set forth, the combination with outer and inner floats and blades or propellers, of stay-chains passing underneath the motor and anchored at opposite ends, adjusting-chains depending from the motor and attached to the said stay-chains, and means for winding the said adjusting-chains.

3. In a current-motor of the character set forth, the combination of outer and inner floats connected to each other, shafts at the opposite ends of the inner floats having sprocket-wheels thereon, endless chains engaging said sprocket-wheels and carrying blades or propellers, drive-shafts on the outer floats connected to said end shafts, drums adjacent to said drive-shafts having means for operating the same, adjusting-chains connected to said drums, and stay-chains running transversely under the motor and anchored at opposite ends, the said adjusting-chains being connected to the stay-chains.

4. In a current-motor of the character set forth, the combination of outer and inner floats, shafts at opposite ends of the inner floats engaged by endless chains carrying blades or propellers, drive-shafts on the outer floats at opposite sides of the endless chains and connected to the said end shafts, said drive-shafts having friction-wheels thereon, adjacent shafts carrying drums and friction-wheels with ratchets, pawls to engage said ratchets, a lever carrying a friction wheel or roller, adjusting-chains attached to and

adapted to be wound on the said drums, and stay-chains extending transversely under the motor and anchored at opposite ends, the said adjusting-chains being connected to the stay-chains.

5. In a motor of the character set forth, the combination of outer and inner floats, shafts at opposite ends of the inner floats, blades or propellers operating the said shafts, and a 10 water-elevator comprising a frame having lower bifurcated ends engaging one of the said end shafts, an endless chain with buckets thereon operated by said engaged end shaft, an upright supporting said frame, and 15 hangers depending from the upper end of the frame and to which a trough is connected.

6. In a current-motor, the combination of outer and inner floats having blades or propellers movable over a portion thereof, drive-shafts on the outer floats, drums adjacent said 20 drive-shafts, adjusting-chains depending from said drums, depending hangers having

grooved rollers therein through which said chains pass, and lower transverse stay-chains anchored at opposite ends and to which the 25 lower ends of the said adjusting-chains are attached.

7. In a device of the character set forth, the combination with opposite chains, of a blade or propeller consisting of two metallic 30 strips having the ends of each bent at right angles and one set of ends placed within and against the other set to dispose the strips in a plane at a right angle to each other, and fastening devices extending through the said 35 ends and adapted to be connected to the chains.

In testimony whereof I affix my signature in presence of two witnesses.

WILLIAM TURNER.
